**MOIST FUEL BURNING FURNACE WITH
DUMPING HEARTH**

Richard E. Sampson, Detroit, Mich., assignor to Bigelow-Liptak Corporation, Detroit, Mich., a corporation of Michigan

Application January 15, 1952, Serial No. 266,490

11 Claims. (Cl. 110—7)

My invention relates to industrial furnaces and, in particular, to hearth floor or grate constructions for moist fuel burning furnaces, e. g., bagasse furnaces.

Many generations ago, the cane sugar industry discovered that the fibrous refuse (bagasse) which remains after the cane is ground in the roller mills could be used as a fuel to produce steam for operating the equipment of the sugar mill. This was an important and valuable discovery because most sugar mills were, and still are, situated where fuel is difficult and expensive to obtain. Furthermore, it was the answer to the problem of how to dispose of the bagasse, this being a problem of no small proportions when it is realized that the individual mills grind from 100 to more than 2000 tons of cane a day during the grinding season. As a consequence, much inventive effort has been devoted to the development of furnaces that would burn this fuel in a manner which was satisfactory to the needs of the cane sugar industry.

It may be said that, in general, the primary consideration of the industry in connection with these furnaces has not been efficiency of combustion, for in most instances there has been a surplus of bagasse, but continuity of operation. This general statement is subject to exceptions which, in recent years, are becoming more common wherein efficiency and cost of installation are also of prime importance—and in these cases the invention of my copending application, Serial No. 266,489, filed January 15, 1952, entitled "Moist Fuel Burning Cell" will be of great interest. Continuous operation is important because of the seasonal nature of this industry. The grinding season lasts only a few months of the year and during this period the mills run at top capacity, twenty-four hours a day. If one of the furnaces is shut down for cleaning or repairs, there is loss of steam and, therefore, a lowering of capacity. In many cases, the mills have found it more economical to have stand-by equipment and operators than to suffer this loss.

Though other methods are used, probably the most popular method of burning bagasse is to pile it in a cell or primary combustion chamber within the furnace. Originally, the pile was supported on a grate through which combustion air was supplied and which could be actuated to dump the ash and residue into a pit below. This proved to be unsatisfactory because the silica thrown into the furnace with the bagasse formed a slag at the high furnace temperatures that clogged the grate so that air couldn't reach the bagasse in sufficient quantities. Furthermore, burning fuel dropped through the grate and burned underneath to rob the air supply and to overheat the grate. These difficulties with the grate-type furnace substantially reduced boiler capacity and resulted in the development of the hearth or grateless furnace in current use. This furnace has a surrounding wall with a door on one side and with air openings or tuyères in the wall so that a forced draft can be supplied to sides of the pile of bagasse on the hearth inside the wall or cell. Gregory-Ward Patent No. 1,952,010 shows a widely used hearth cell design, the so-called Cook or horseshoe design, and one with which the present invention may be used, as illustrated hereinafter.

While this, the hearth type of furnace, is regarded by many as the best design available, it has its drawbacks. From the standpoint of continuous operation, a serious weakness of this type of furnace is that it must be cleaned out every eight hours or so. In the past, this has been done by opening the door in the hearth wall so that the

2

operators could hoe out the ash and break off the slag formations. Considerable time was consumed since the furnace was quite hot and unpleasant for the workers. Furthermore, during at least the cleaning period, the furnace door was open and this admitted excess air that actually acted as a coolant to result in still further loss of steam. Those in the art will be familiar with other important drawbacks incident to the cleaning of this type of furnace, such as early destruction of base masonry due to prodding in the course of slag removal.

In overcoming these drawbacks, my invention makes it possible to clean a furnace of this type in only a matter of minutes, and the job is largely mechanical rather than manual. I use a movable hearth floor or grate to support the pile of moist fuel and which preferably tilts upwardly about a horizontal axis adjacent the hearth door so that ashes, etc., are mechanically deposited at the door of the furnace through which they can be quickly removed without first cooling down the furnace. My tiltable floor fits close enough to the side wall of the hearth or cell so that it scrapes it as it is tilted, thereby removing slag and other material that may be clinging to it. The tiltable floor can be installed in existing installations as well as in new installations; and, in order to insure its long life, I prefer to mount it in and at the top of a pit beneath the furnace which is in communication with the forced draft furnished to the tuyères so that the floor will be continuously cooled.

My invention is shown by way of illustration in the accompanying drawings, wherein:

Figure 1 is a vertical section through a portion of bagasse furnace installation embodying a tiltable floor or grate constructed in accordance with the invention;

Fig. 2 is a horizontal section taken along the line 2—2 of Fig. 1;

Fig. 3 is a vertical section taken along the line 3—3 of Fig. 1;

Fig. 4 is a vertical section taken along the line 4—4 of Fig. 3;

Fig. 5 is a vertical section taken along the line 5—5 of Fig. 3;

Fig. 6 is a vertical section taken along the line 6—6 of Fig. 2;

Fig. 7 is a section taken along the line 7—7 of Fig. 6; and

Fig. 8 is an enlarged view of the joint between the tiltable floor and fixed ledge.

The hearth floor or dumping grate of this invention is shown in the drawings in connection with improved features for a bagasse furnace such as illustrated in my copending application, Serial No. 266,489, filed January 15, 1952, entitled "Moist Fuel Burning Cell," the specification and drawings of which are incorporated herein by reference. Briefly, this type of furnace has preferably a hearth cell construction of the so-called Cook design; that is, it is ordinarily U- or horseshoe-shape such as illustrated best in Fig. 2. The major portion of the wall of the cell which, in accordance with the invention of said copending application, is constructed of a series of horizontal courses formed from individual blocks of tile 3 which rest upon a lower course of cast iron blocks 5 that are staggered in height. The various blocks and courses are mechanically keyed together and forced laterally against each other and longitudinally against masonry pillars 6 at the front of the cell by means of U-shaped retaining bars 7 that fit in aligned notches 9 in each horizontal course of blocks, the ends of the bars being secured to the pillars 6 or to suitable posts or abutments at the front of the furnace. The tile blocks 3, the cast iron blocks 5, and the pillars 6 have suitable tuyères 11 whereby air under forced draft from plenum chamber 13 which is furnished to the outside of the cell wall may pass through the wall to the inside of the cell, as described in more detail in my copending application. The air for this purpose is supplied by a blower or the like to the chamber 13 that is located at the rear of the cell 1. Gaseous products resulting from burning of the bagasse or other moist fuel in the cell rise through the throat 15 of the furnace and pass over the boiler tubes (not shown), it being apparent to those

in the art that the furnace of Fig. 1 is of the well-known Ward "bottleneck" design.

The moist fuel may be fed to the cell 1 by means of an inclined chute 17 through which it slides by gravity to land on the hearth floor or grate 19 of the cell. Preferably, a pair of Dutch doors 21 are provided at the front of the furnace and constructed in accordance with the invention disclosed in the copending application of my co-worker, Robert A. Banck, Serial No. 314,901, filed October 15, 1952, entitled Moist Fuel Burning Furnace Door Construction, which application is assigned to the same party as the present application. Those in the art will appreciate, however, that the invention may be used with cells having ordinary door constructions and, in fact, it is intended that the invention be capable of installation in existing furnaces. The doors are used to permit operators of the furnace to insert suitable pokers or hoes into the furnace or to enter the furnace. The furnace has a masonry sill 23 immediately in front of the doors 21 and which is adjacent ground level or the level of the floor 24 on which the operators stand. The sill 23 is also on a level with or above the bottom of the lower of the doors 21 whereby material on the sill may be easily shoveled or pulled out of the lower door.

In accordance with the present invention, the hearth or grate 19 is contoured to fit the inside of the wall of the cell 1, due regard being had to expansion, and is pivoted at its front end so that it may be tilted about a horizontal pivot axis permitting its rear end to rise whereby material on the hearth will slide by gravity 30 downwardly on to the sill 23 from which it can be readily removed through the doors 21. A particular feature of importance is the fitting of the hearth plate or grate 19 to the inside of the walls of the cell. This enables the hearth 19, when tilted, to scrape the slag and other material clinging to the wall from the inside faces of the blocks 3 and 5 and eliminates the manual prodding that has been necessary heretofore.

While within the broad purview of this invention the hearth plate or grate 19 may be constructed in various ways, it is preferably formed in the manner illustrated in the drawings. Thus, it consists of left- and right-hand central castings 25 and 27 and left- and right-hand outer castings 29 and 31. These castings extend from the front to the rear, that is longitudinally, of the cell. They may be made from ordinary cast iron, heat-resistant cast iron, cast steel, or other material, as desired.

The central castings 25 and 27 have longitudinal downwardly extending flanges 33 formed on either side thereof and also transverse downwardly extending flanges 35 at the front and rear. The innermost longitudinal sides of the outer castings 29 and 31 are also provided with longitudinal downwardly extending flanges 34 which are counterparts of and substantially identical to the flanges 33. Suitable pads 37 are cast on the flanges 33 and 34 and serve as areas of engagement among the various castings and are readily machined to give the proper fit. The hearth floor sections are bolted tightly together by transversely extending bolts 38 that pass through aligned holes in the pads 37, as clearly seen from Fig. 3. The several hearth plate castings are formed with suitable reinforcing ribs on the underside thereof in addition to the flanges which extend around them each peripherally. The reinforcing construction also includes a main and centrally located vertical transversely extending reinforcement structure or keel 39 which includes a bottom horizontal flange 41. The keel and flange are made up of aligned sections cast in each of the component plates of the hearth floor 19. The flange 41 serves as a convenient attachment area for a floor-lifting means. For such purpose, the bracket 43 is bolted to the flange 41 and includes bifurcated portions that receive the end of the piston rod 45 for a pressure fluid cylinder 47, a pivot pin 49 extending through the end of the rod and being journaled in and secured to the bracket 43.

The bottom of the cylinder 47 has bifurcated portions 51 which receive a bracket 53 that is secured in position in the bottom of a pit 55 below the hearth floor, the portion 51 and the bracket 53 being interconnected by a transverse pivot pin 54. It will be seen that the keel 39 reinforces the central area of the floor and that the cylinder 47 and rod 45 furnish some measure of support also to the floor in the central areas thereof. The pit 55 preferably communicates, as shown in Fig. 1, with the air chamber 13 so that air draft from the chamber 13 can

cool the hearth plates. Apertures 59 in the plates, as well as the clearances between the flanges 33 and 34 occasioned by engagement of pads 37, will enable some air to reach the bottom of the pile of bagasse and, if this is relied upon, it will be seen that these openings can be readily cleaned of slag or the like when the floor is tilted. Communication of the pit 55 with the chamber 13 also provides a means of access to the pit whereby the ash and other material which happened to drop into the pit may be periodically cleaned out. The cylinder 47 is preferably an air-operated unit but in any case will, of course, have the required circuit and controls such as fluid inlet and outlet connections 61 that pass through suitable control valves (not shown) and are connected to a suitable source of fluid pressure (not shown).

For the purpose of pivotally mounting the forward end of the hearth floor 19, bifurcated brackets 63 may be bolted to the bottom of central portions of the front ends of plates 29 and 31. The bifurcated portions of these brackets receive brackets 65 that are secured to a ledge 67 below and to the rear of the sill 23. Transverse pivot pins 69 pivotally interconnect the brackets 63 and 65. The rear edge of the hearth floor may be supported on a ledge formed around the periphery of the cell by a suitable transversely extending angle bar 71 secured to the cell base 72. The cutout sections 73 at the rear of the various hearth plate sections fit on the bar 71. The supports for the hearth plate 19 are preferably located so that the top of the hearth plate 19 is flush with the sill and these two surfaces are preferably flush with the bottoms of the lowest course of blocks 5.

It can now be readily seen that by applying pressure fluid to the cylinder 47, the piston rod 45 will be extended to pivot the hearth 19 forwardly and upwardly about the axis of the pivot pins 69. As a result, the ash or other material on the hearth plate will slide onto the sill 23 from which it can be readily removed through the doors 21. During this movement of the hearth plate 19, it will scrape the cell wall to remove slag and other clinging materials. The sill 23 has a projecting lip 75 that remains close to the surface of the floor 19 when the latter is tilted to prevent material from sliding into the pit 55. The tapered inside faces of the pillars 6 tend to funnel the ashes toward the doors 21 and thus facilitate their removal.

The invention thus makes it possible to quickly and thoroughly clean the furnace with a minimum of manual labor and shut-down time and with a minimum admission of excess air. The fact that the tilttable floor is air cooled will tend to prevent sticking or adherence of ash and slag and therefore facilitate their removal through the doors. It will be appreciated that the invention comprehends within its scope various modifications of the detail structure herein illustrated. It is, therefore, evident that the invention is not limited to the precise details of construction shown herein.

I claim:

1. In a moist fuel burning furnace comprising side wall means defining a moist fuel cell, the combination of a door in said side wall means, a sill in the cell adjacent the lower side of the door, a movable floor in the cell, said floor being pivoted on a horizontal axis at the edge thereof adjacent said sill, said axis being substantially parallel to the plane of said door so that upon upward movement of the floor about said axis material on the floor will slide downwardly on to the sill, and means operatively associated with the floor for moving the floor upwardly about said pivot axis.
2. The invention set forth in claim 1 wherein said floor fits closely enough to said side wall means so that upon upward movement thereof it functions as a scraper for the side wall means.
3. The invention set forth in claim 1 including a support for the edge of the floor remote from said sill arranged to allow the floor to rest thereon in a level position flush with the sill.
4. The invention set forth in claim 3 wherein said moving means for the floor is power operated.
5. The invention set forth in claim 4 including means defining a pit below said floor, said power operated moving means comprising a pressure fluid cylinder and piston device disposed in said pit and operatively connected to the floor.
6. The invention set forth in claim 5 including means associated with said pit for supplying air thereto to cool

the floor, said pressure fluid cylinder and piston device being connected to a central area of the floor and serving as a support therefor.

7. The invention set forth in claim 6 including means providing a ledge below the top surface of the sill and at the edge of the sill adjacent said floor, said floor being pivoted on transversely spaced and aligned pivot brackets located on said ledge, said brackets defining said pivot axis and said axis being located below the top surface of the sill and spaced slightly from the edge of the door adjacent said sill so that said edge and a portion of said floor projects over the pivot axis toward the sill, said sill including a lip projecting from the top surface thereof over said ledge and toward the floor and to a position closely adjacent to said floor edge, the sill being recessed away from the floor beneath said lip to permit tilting of said floor portion and floor edge beneath said lip while preventing substantial clearance between the surface of the floor and the sill.

8. The invention set forth in claim 7 wherein said floor fits closely enough to said side wall means so that upon upward movement thereof it functions as a scraper of the side wall means.

9. In a moist fuel burning furnace, side wall means defining a moist fuel cell, a door in said side wall means, a movable floor in the cell defining a substantially horizontal moist fuel supporting surface covering a major part of the area of the cell, said floor being substantially impervious to the passage therethrough of moist fuel and its ash, said floor having a first end adjacent said door and a second end remote from said door, means mounting said floor for angular movement to a dumping position in which the first end is substantially on a level with

the bottom edge of said door and the second end is substantially higher than the first end so that said surface is on an angle to the horizontal and material thereon will tend to slide downwardly toward the first end and thus said door, and means operatively associated with said floor for moving said floor to said dumping position.

10. The invention set forth in claim 9 wherein the floor fits closely to said side wall means and upon movement thereof to said dumping position functions as a scraper for the side wall means.

11. The invention set forth in claim 9 including means defining a pit below said floor, said floor moving means comprising a power operated member mounted in said pit and operatively connected to a central area of said floor and serving as a support for the floor as well as a means for moving the floor to dumping position.
